UNITED STATES PATENT OFFICE.

ROBERT W. KING, OF TORONTO, ONTARIO, CANADA.

ROTARY PUMP.

Application filed October 11, 1926. Serial No. 141,004.

This invention relates to rotary compression pumps, of the eccentric displacement type, in which a rotary piston provided with sliding blades is eccentrically mounted in a stationary casing or cylinder, and the cylinder is provided with a perforated barrel adapted to rotate with the piston. Hitherto the said barrels have been mounted concentrically in the pump casings and have not been so arranged as to automatically take up wear.

The object of my invention is to construct a device of the kind described, which is highly efficient, silent, of cheap and simple construction, easily adjusted or repaired and which will retain these features when made in the smaller sizes. Other objects I have in mind will hereinafter appear.

Improved means for lubricating the pump is also provided.

An adjustable bearing is provided for receiving end pressure of driving shaft of the pump.

My invention is hereinafter more fully described and illustrated in the accompanying drawings in which

Fig. 1 is a cross section of my improved pump;

Fig. 2 is a longitudinal section of the same;

Fig. 3 is a plan view of part of the ring and casing; and

Fig. 4 a plan view of shaft end bearing.

In the drawings like numerals of reference indicate corresponding parts in the different figures.

The pump comprises the casing cage or cylinder *a*, supporting an eccentrically mounted driving shaft *b*, rotated by means not shown, a piston *C* attached to the shaft and containing a series of sliding blades *G*, and the ring *i*. The latter surrounds the piston and blades.

The casing *a* has suitable removable covers *a'* and has opposing suction and compression chambers *g* and *h*. These chambers open to the interior of the casing and are comparatively narrow relative to the entire width of the casing, and are respectively connected to the entrance and exit ports *g'* and *h'* of the pump.

The piston *C*, suitably connected to the driving shaft *b*, is provided with a centrally located chamber *l* which communicates with the channels in which the blades slide. The said chamber is of such a diameter that in the process of machining the channels they

will connect with the chamber and one another through the chamber without further machining being required. In pumps of this nature when sliding blades are used, and especially when blades of thick fibre, of less specific gravity than comparatively thin blades of iron or steel are used, it is important that no hindrance to their free action will occur. When the channels for the blades are cut into a solid piston the blades have to expel the fluid as they enter the channels, and are hindered by suction as they leave. The construction described overcomes this difficulty as thereby the pressure in the fluid spaces and consequently in the channels remains substantially constant because as soon as some blades are advancing a like number are receding. This construction also facilitates the lubrication of the blades in a manner hereinafter described.

The ring *i* is loosely fitted in and unjournalled concentrically with the casing *a*, and is free to move in any direction within the limits of its cage to find its natural position on the interior of the casing. The ring thus advances and maintains contact with the hereinafter described parts of the casing as wear takes place. The ring is caused to revolve by its frictional contact with the blades. The central portion only of the periphery of the ring is liberally perforated so that when in place in the cylinder *a*, its perforations 12 are opposite the chambered portions of the casing. The imperforated end portions of the ring form liberal wearing surfaces to contact with the unchambered portions of the interior of the casing. It is essential to the life of the pump that the ring be accurately machined to a true circle smoothly polished on its outside periphery, be accurately balanced and be free to locate itself in the casing. There are two locations, only, in the inner periphery of the casing where it is necessary for the ring to contact in order to form stops to prevent or minimize the escape of the fluid from the compression to the suction side of the pump. These stops *j* and *K* are located between the suction and compression chambers *g* and *h*. The ring *i* tends by means of the pressure of the fluid passing therethrough to contact with these stops in the same manner as a valve to its seat. The pressure, due to the flow of fluid, is maintained low enough to permit of the free rotation of the ring, while sufficient to check the back flow referred to,

by suitably proportioning the perforations of the ring.

The stop portion K extends through an arc of greater length than the length of the arc between the adjacent blades G so that it will close all the perforations 12 between the blades contacting with the ring beneath the stop portion whereby the fluid under compression cannot pass through the said perforations to escape from the compression to the suction sides of the pump.

The stop portions j and K are preferably made with a shell construction filled with anti-friction metal formed therein in any suitable manner while in place on the ring or on a ring standard specially prepared for that purpose. Thus an accurate fit to the actual periphery of the ring is obtained at minimum expense.

20 The piston C is machined substantially smaller in outside diameter than the inside diameter of the ring to prevent contact therewith.

When an air compressor pump is directly connected to an electric motor the speed at which it is driven is predetermined and unalterable according to the nature of the electric current employed. The pump should be designed to compress the maximum amount of air at the maximum pressure likely to be required with a margin to allow for the usual loss of air in this type of pump. When the full pressure of air is not required, a common practice is to reduce the supply by means of a valve in the supply pipe and permit the unused portion of the compressed air to return by suitable passageways to the suction side of the pump. This air is then recompressed along with the new air that enters the suction port. The pump and motor are thus operated at full capacity at all times which reduces the efficiency of both, thus increasing the cost of upkeep and it also wastes electric energy. To overcome

45 these objectionable features I provide a bypass 1 having a valve 1' and forming a communication between the compression chamber h and the interior of the ring at 2. The point 2 is so located that the air in the pockets formed by the blades G, ring i and piston C will not be fully compressed. When the valve 1' is opened all the air at a reduced pressure passes from the pockets.

50 The pump parts are lubricated as follows. An oil reservoir, not shown, is situated so that the level of the oil is below the bottom of the pump so that oil cannot flow when the pump is at rest. Suitable pipes or tubes, not shown, connect the bottom of the oil reservoir with the combination needle valve and sight feed fittings 6, and 6', from which the oil is conducted by pipes or tubes to the journals of the pump. Suitable passages 21 and 21' carry the oil round the 55 journals and these grooves communicate with

the conduits 11 and 11' which communicate with the expanding pockets formed by the piston, blades and ring at 9 and 9'. The suction at the point 9, which is created by revolving the piston, causes the oil to be drawn from the reservoir through the fitting 6 to the passages 21 for lubricating the main bearing p. The oil is then drawn through the conduit 11 into the said expanding pockets where it lubricates the sliding blades G. The most important wearing parts are thus first oiled while the oil is cool and in liquid form. Oil also passes through the perforations in the ring to lubricate it and any sediment or heavy condensed oil passing into the compression chamber h will be directed downwardly by the baffle 4 into the lower part of the chamber. A drain pipe 5 is adapted to drain the lower part of the chamber. Some of the oil drawn into the pockets will be forced, when the air is compressed in the pockets, along the blades G into the chamber l. This chamber communicates by means of passages m and n with the thrust bearing o which is carried by the bearing p'. The passage 21' communicates with the passage n whereby the outboard bearing p' is lubricated. If it is desired this bearing p' may be lubricated with fresh oil by opening the valve in the fitting 6' which controls the flow of oil through the conduits 21', 11', and 9', and thus ultimately to the chamber C.

55 In my description I have described the pump for use in pumping air. It should be understood, however, that the construction described is equally applicable for use with other fluids and that modifications, especially in the relative positions and directions of the inlet and outlet ports, may be made in the construction without departing from the spirit of my invention.

60 What I claim is:

1. A rotary engine or pump comprising a cylinder casing; a rotary piston eccentric to the cylinder; a plurality of blades slideable in the piston; suction and compression chambers formed at opposite sides of the cylinder and of less width than that of the cylinder; and an unjournalled floating ring of the full width of the cylinder and interposed between the cylinder and piston, the ring being free to rotate with the piston and blades and having perforations located only intermediate the ends thereof for communication with the suction and compression chambers, the area of the perforations being proportioned to cause a frictional pressure of the ring against the casing, due to the flow of fluid, less than the frictional driving pressure of the blades against the ring.

65 2. A rotary engine or pump comprising a cylinder casing; a rotary piston eccentric to the cylinder; a plurality of blades slideable in the piston; suction and compression cham-

bers formed at opposite sides of the cylinder and of less width than that of the cylinder; an unjournalled floating ring of the full width of the cylinder and interposed between the cylinder and piston, the ring being free to rotate with the piston and blades and having perforations located only intermediate the ends thereof for communication with the suction and compression chambers; 5 and a replaceable stop for engaging the ring to prevent the escape of fluid from the compression to the suction chambers, suction chamber and stop being positioned so that the flow of fluid towards the compression 10 chamber has a tendency to force the ring against the said stop, the area of the perforations being proportioned to cause a frictional pressure of the ring against the stop, due to the flow of fluid, less than the frictional driving pressure of the blades against 15 the ring.

3. A rotary engine or pump comprising a cylinder casing; a rotary piston eccentric to the cylinder; a plurality of blades 20 slidable in the piston; suction and compression chambers formed at opposite sides of the cylinder and of less width than that of the cylinder; an unjournalled floating ring of the full width of the cylinder and interposed between the cylinder and piston, the ring being free to rotate with the piston and blades and having perforations located intermediate 25 the ends thereof for communication with the suction and compression chambers; and 30 two stops for engaging the ring to prevent the escape of fluid from the compression to the suction chambers located at the compression side of the device, suction chamber and stop being positioned so that the flow of 35 fluid towards the compression chamber has a tendency to force the ring against the said stops, one of the said stops being adjustably carried in the casing.

4. A rotary engine or pump comprising a cylinder casing; a rotary piston eccentric to the cylinder; a plurality of blades slidable in the piston; suction and compression chambers formed at opposite sides of the cylinder and of less width than that of the cylinder; an unjournalled floating ring of the full width of the cylinder and interposed between the cylinder and piston, the ring being free to rotate with the piston and blades and having perforations located only intermediate 50 the ends thereof for communication with the suction and compression chambers; and two adjustable stops for engaging the ring to prevent the escape of fluid from the compression to the suction chambers located 55 at the compression side of the device, and so positioned in relation to the interior of the cylinder and to the outer periphery of the ring member that the fluid passing to the discharge tends to force the ring into contact 60 with the stop members.

5. A rotary pump comprising a cylinder having an inlet and an outlet and suction and compression chambers; a piston eccentric to the cylinder; a plurality of blades slidable in the piston; a loosely fitted ring 70 interposed between the cylinder and piston and provided with perforations; means for preventing leakage from the pressure side of the device to the suction side; a conduit forming a communication between the compression chamber and the interior of the ring 75 whereby air under low pressure may be delivered to the compression chamber; and a valve in said conduit.

6. A rotary engine or pump including a cylindrical casing; a piston journaled in the casing provided with a plurality of sliding blades and forming expanding and contracting pockets therebetween; an oil supply; a conduit communicating with the pockets 85 when expanding, whereby the oil is sucked into the said pockets.

7. A rotary engine or pump including a cylindrical casing; a piston journaled in the casing provided with a plurality of sliding 90 blades and forming expanding and contracting pockets therebetween; an oil supply conduit communicating with the pockets when expanding whereby oil is sucked into the interior of the said pockets, the said conduit 95 also being adapted to first supply the journal of the pump with oil.

8. A rotary engine or pump including a casing; a piston journaled in the casing provided with a plurality of sliding blades 100 forming contracting and expanding pockets therebetween; a chamber in the piston adapted to receive the inner ends of the sliding blades; an oil supply; conduits connecting the oil supply with the interior of the 105 pockets when expanding, the resulting pressure in the pockets when contracting forcing oil along the sliding blades into the chamber; and conduits connecting the said chamber with the interior of the said pockets 110 when expanding.

9. A rotary engine or pump of the class described containing a piston mounted on a shaft journaled in the casing; a chamber in the piston; oil conduits to the chamber 115 from the suction side of the piston; an end thrust bearing for the shaft; and a conduit from the chamber to the thrust bearing, whereby the same may be lubricated by oil from the chamber.

10. A rotary engine or pump of the class described containing a piston mounted on a shaft journaled in the casing; a chamber in the piston; oil conduits to the chamber from the suction side of the piston; an end thrust bearing for the shaft; and a conduit 125 from the chamber to the thrust bearing, whereby the same may be lubricated by oil from the chamber; a connecting conduit with the original oil supply whereby both 130

the outer journal and end bearing can be lubricated with fresh liquid oil if desired; and conduits connecting said last mentioned conduit with the suction side of the piston.

5 11. A rotary engine or pump comprising a cylinder casing; a rotary piston eccentric to the cylinder; a plurality of blades slidable in the piston; inlet and outlet ports at opposite sides of the cylinder; an unjournalled floating ring interposed between the cylinder and piston, the ring being loose in the cylinder and free to rotate with the piston and blades; and two stop portions on the interior periphery of the cylinder adjacent opposite sides of and opposite the inlet port and the outlet port into contact with which the ring is lifted by the pressure of the fluid passing through the engine or pump.

12. A rotary engine or pump comprising a cylinder casing having opposite inlet and outlet ports; a rotary piston eccentric to the cylinder having at least three slidable blades; an unjournalled loosely fitted perforated ring of an external diameter substantially smaller than the internal diameter of the casing free to rotate with the piston and blades and arranged to seat against the casing at the outlet side thereof, whereby, when the piston is rotated at high velocity, a current of air or other fluid passing through the casing from the inlet to the outlet will compel the ring to locate itself opposite the exit forming with the casing an obstruction so that only the fluid passing through the perforations made in the ring will be discharged at the exit.

13. A rotary engine or pump comprising a

cylinder casing having opposite inlet and outlet ports; a rotary piston eccentric to the cylinder; a plurality of blades slidable in the piston; suction and compression chambers formed at opposite sides of the cylinder and of less width than that of the cylinder; an unjournalled floating ring of the full width of the cylinder and piston, the ring being free to rotate with the piston and blades and arranged to seat against the casing at the outlet side thereof and having perforations located intermediate the ends thereof for communication with the suction and compression chambers, whereby, when the piston is rotated at high velocity, the induced current of fluid passing through the casing from the inlet to the outlet will cause the ring to float and seat itself in a position obstructing the discharge of fluid from the cylinder so that only the fluid compressed in its passage through the ring will be discharged at the exit from the cylinder.

14. A rotary engine or pump including a casing; a piston journalled in the casing provided with a plurality of sliding blades forming contracting and expanding pockets therebetween; a chamber in the piston adapted to receive the inner ends of the sliding blades; an oil supply; and conduits connecting the oil supply with the interior of the pockets when expanding, the resulting pressure in the pockets when contracting forcing oil along the sliding blades into the chamber.

Signed at Toronto, Canada, this 25th day of September, 1926.

ROBERT W. KING.
